CLAIM

The ornamental design for a pet mat with embossing pattern, as shown and described.

DESCRIPTION

FIG. 1 is a top plan view of a pet mat with embossing pattern embodying my new design;

FIG. 2 is a front side view of the pet mat with embossing pattern of FIG. 1;

FIG. 3 is a right side view of the pet mat with embossing pattern of FIG. 1;

FIG. 4 is a left side view of the pet mat with embossing pattern of FIG. 1;

FIG. 5 is a back side view of the pet mat with embossing pattern of FIG. 1; and,

FIG. 6 is a bottom plan view of the pet mat with embossing pattern of FIG. 1.

The broken lines surrounding the design represent the boundaries of the claim and form no part thereof. A specific length and width of the pet mat with embossing pattern forms no part of the claimed design. The thickness of the pet mat with embossing pattern forms no part of the claim. The broken lines in the figures form no part of the claimed design.
